[57] CLAIM

The ornamental design for a fisherman's vest, as shown
and described.

DESCRIPTION

FIG. 1 is a front elevational view of a fisherman's vest
showing my new design;

FIG. 2 is a rear elevational view thereof;

FIG. 3 is a reduced front perspective view thereof,
shown from the left side;

FIG. 4 is a reduced front perspective view thereof,
shown from the right side;

FIG. 5 is an enlarged fragmentary view thereof, the
upper left hand pockets shown in detail.

FIG. 1

FIG. 2

FIG. 3

FIG. 4
